US00D408477S

United States Patent [19]

Arnold et al.

[11] Patent Number: Des. 408,477

[45] Date of Patent: **Apr. 20, 1999

[54] STATIONARY EXERCISE DEVICE

[75] Inventors: Peter J. Arnold, Seattle; Philip S. Lamb, Bothell, both of Wash.

[73] Assignee: Precor Incorporated, Bothell, Wash.

[**] Term: 14 Years

[21] Appl. No.: 29/086,289

[22] Filed: Apr. 9, 1998

[51] LOC (6) Cl. 21-02

[52] U.S. Cl. D21/668; D21/670

[58] Field of Search D21/662, 668, D21/689, 670; 472/51, 52, 53, 57, 71, 72
